UNITED STATES PATENT OFFICE.

WILLIAM H. FLINN, OF DETROIT, MICHIGAN.

ROTARY EXPLOSIVE-ENGINE.

1,284,083.

Specification of Letters Patent.

Patented Nov. 5, 1918.

Application filed September 20, 1918. Serial No. 121,112.

To all whom it may concern:

Be it known that I, WILLIAM H. FLINN, a citizen of the United States of America, residing at Detroit, in the county of Wayne 5 and State of Michigan, have invented certain new and useful Improvements in Rotary Explosive-Engines, of which the following is a specification, reference being had therein to the accompanying drawings.

10 This invention relates to gas engines or internal combustion motors of the rotary type and to an arrangement thereof whereby the compression in the combustion chamber gradually reaches its maximum through the 15 efforts of successive rotary members that have previously been acted upon by the expansion of exploded gases in the same chamber. The invention includes means whereby the necessary clearances, joints and cooling 20 are obtained, and whereby the friction between the necessary contacting parts is reduced to a minimum. The invention also includes means and mode of operation whereby a unit may be multiplied as desired 25 to obtain a power plant of this type that is necessary to meet any particular requirement of service.

The invention consists in the matters hereinafter set forth and more particularly 30 pointed out in the appended claims.

In the drawings,

Figure 1 is a view in transverse section, partially broken away and partially in elevation, of a motor that embodies features of 35 the invention; Fig. 2 is a view in longitudinal section on or about line II—II of Fig. 1, parts being shown broken away and in elevation.

Fig. 3 is a view in transverse section taken 40 on or about line III—III of Fig. 2;

Fig. 4 is a view in detail of a preferred form of abutment, and

Fig. 5 is a view taken on or about line 45 V—V of Fig. 1.

Referring to the drawings, a suitable substantially cylindrical or annular shell 1 having a central circular chamber, is mounted as by extensions or lugs 2 on a main frame 3 that is suitably ribbed and flanged to combine strength with lightness. Side walls 6 50 that are suitably secured against the annular faces of the shell 1, form therewith a closed casing.

A main drive shaft 7 is retained by suitable 55 bearings, such as indicated at 8, for

example, and by end thrust collars 9, to rotate in concentric relation with the main chamber of the shell. A web member 10 in the chamber is secured to a flange 11 formed on or secured to the shaft 7 and carries a rim 12 that rotates in the chamber of the shell, a pair of packing rings 13 providing a close joint between the rim and chamber wall on either side of an exhaust passage 14 and a compression passage 15. Both the exhaust 60 and compression passages are segmental and eccentric to the axis of rotation of the main shaft and are swept successively by abutments 16. The latter are projected from radial slots in the web 10 by means of suitably arranged spring members 17. Preferably spring perch blocks 18 journaled on studs 19 against the sides of the web 10 carry the members 17 which extend from them to engage a pair of abutments each, whereby 70 the spring pressures are equalized, as only one of a pair of abutments at a time is fully pushed in while moving from one passage to the other.

A compression or explosion chamber 20 is in communication through a passage 21 with the compression space 15, a suitable valve 22, of the conical plug type, with end compression spring 23, controlling this passage. A valve stem 24 of the plug carries 80 a cam finger 25 that rides on a cam ring 26, suitably secured to the annular face of the rim 12. As indicated in Figs. 1 and 2 the valve is in closed position as the finger is riding on the high spot of the cam ring. 90 An exhaust valve 27 similar to the valve 22, controls an outlet passage 28 that forms communication between the chamber 20 and the expansion space 14. A cam finger 29 operates the valve 27 through the medium 95 of the cam ring 26. This finger however, being in a different plane than the finger 25 of the inlet valve so that while the latter falls to the low spot of the ring over a release shoulder 31 of the cam ring, the finger 100 29 reaches a low spot over a release shoulder 30, the latter being timed to allow the closing of the valve 27 a short time after the valve 22 is opened. An inlet nipple 33 is used to connect the source of fuel supply 105 with the compression space 15, as indicated plainly in Fig. 3, and this inlet is at a point where the abutment, as plainly seen in Fig. 3 has already traversed a part of the space 15 and thereby created a slight 110

vacuum to aid in the intake of the fuel. An outlet boss 34 forms the exhaust opening of the motor from the passage 14, a clearance channel 35 being provided which is bridged by the abutments as they sweep around the periphery of the shell.

The combustion chambers 37 and 20 and the explosion or expansion passage 14 are water jacketed as indicated at 36 by means 10 of a suitable outer wall.

A compression or explosion chamber 37 is connected to the passages 14 and 15 by suitable valves similar to the valves 22 and 27 of the chamber 20, but in reverse position, the inlet valve 38 being indicated in Fig. 2. A cam finger 39 that controls this valve rides on a ring 40 on the opposite annular face to the ring 26, the cam rings being set diametrically opposite so that the chambers 20 and 37 have opposite phases of operation. When the valves of the chamber 20 assume the position shown in Fig. 1, the valves of the chamber 37 assume the position indicated by the dotted lines in 25 Fig. 3.

As details of good construction, an oil drain channel 41 has a spring 42 that presses wicking 43 or the like upwardly to bear against and lubricate the periphery of the 30 rim 12 and the rounded extremities of the abutments. This rounded contour of the abutment ends insures contact with the inner periphery of the shell and of the passages 14 and 15, while side shoes 44 projected by 35 springs 45, aid in keeping the side joints between the abutments and walls measurably tight.

In operation, the abutments as they sweep the passage 15, gradually force the charge 40 ahead into the chamber 20, for example, until the valve 22 has assumed the position shown in Figs. 1, 2 and 3. Explosion then takes place at the moment that the high point of the cam ring has underrun and 45 swung up the finger 28 opening the outlet valve 27 and the force of the discharge is expended upon the abutments as they successively pass through the channels 14. While the explosive force of this charge is 50 thus being exerted on the abutments for half the circumference of the rim 12, the companion abutments are sweeping the channel 15 and forcing the intake gases into the companion chamber 37. Then the latter fires and as a result the explosion is 55 exerted on the abutments that have just charged this chamber while the companion abutments are recharging the chamber 20. By proper timing of the intake and outlet 60 valves scavenging of the compression chambers is obtained, both valves being held open sufficiently for this purpose. It is found in practice that the extension of the passage 15 to a point between the inlet 33 and the 65 outlet 34 produces sufficient vacuum by the

sweeping of this part by the abutments as they approach the inlet 33 to effectively indraw the gases of the fuel supply.

In addition to the lubrication of the main running parts as indicated, bearing caps 46, 70 with deflecting plates 47, having screw threads 48 that deflect lubricant back again along the shaft 7, together with other details of construction in accordance with good shop practice afford an oiling system that 75 effectively prevents excessive wear. It is to be understood that the usual connections are made for distribution of the firing current and as an example of how readily the parts are operated, a main driving gear 49 is 80 shown on the shaft 7 within the casing, from which gear trains may be taken off to operate the timing and sparking systems.

One feature of the construction is the great compression obtained by the successive charge increments. Another feature is the utilization of the explosive force of the gases against the succeeding abutments after the initial shock of discharge. A further feature is the ability to combine units to 90 operate on the same shaft, by a proper setting of the cam rings for each in timed relation to the companion cycle.

Obviously, changes in the details of construction may be made without departing 95 from the spirit of my invention and I do not care to limit myself to any particular form or arrangement of parts.

What I claim is:

1. In a rotary internal combustion motor, 100 a casing having a circular chamber with segmental compression and expansion spaces formed in the periphery, a web member rotatable in the casing chamber, abutments reciprocable in the web member projecting 105 into the compression and expansion spaces, spring members rotatably mounted on the web sides, engaging the abutments, a pair of combustion chambers in the casing, rotary valves, each controlling communication between the circular chamber and a compression and expansion space, and means on the web for periodically oscillating the valves in timed relation to the movement of the abutments.

2. In a rotary internal combustion motor, 116 a casing having a circular member with segmental compression and expansion spaces formed oppositely in the periphery thereof, a web member rotatable in the chamber of 120 the casing, abutments radially arranged in the web member to project from the periphery thereof into the compression and expansion spaces, spring perches journaled on the sides of the web, spring members each 125 mounted on a perch and adapted to engage a pair of abutments, a pair of combustion chambers in the casing, rotary valves each controlling communication between a chamber and a compression or an expansion space. 130

cam fingers for oscillating the valves, and cam rings on the web adapted to operate the cam fingers.

3. In a rotary internal combustion motor, 5 a main frame, a main drive shaft journaled therein, a casing on the main frame having a circular chamber through which the shaft extends in concentric relation, the walls of the chamber having segmental, eccentric 10 compression and expansion spaces, a web member on the shaft filling and rotating in the chamber, abutments reciprocable in radial guideways in the web, means yieldingly projecting the abutments to sweep the chamber walls and the compression and expansion 15 spaces, the casing having a pair of combustion chambers in communication through the inlets thereof with the compression space and through the outlets thereof with the expansion space, valves rotatable in the chamber inlets each provided with a cam finger, 20 valves rotatable in the chamber outlets each provided with a cam finger, and cam rings mounted on the web and adapted to operate 25 the fingers to open the valves in timed relation to the engine cycle.

4. In a rotary internal combustion motor, a main frame, a main drive shaft, bearings for the shaft secured in the main frame, an 30 annular shell secured on the main frame in concentric relation to the shaft, side walls on the shell forming therewith a closed casing having a circular chamber substantially concentric with the shaft, a web member secured on the shaft to rotate in the chamber which it substantially fills, and provided with radial guide slots, abutments longitudinally reciprocable in the radial guide slots, 35 spring perches secured on the face of the web, springs mounted on the perches each engaging a pair of abutments for projecting them against the walls of the chamber, a pair of combustion chambers formed in the shell each in communication through a compression space eccentric to the web member with an inlet to the shell, and in communication as to the outlets thereof respectively, and an eccentric expansion space with a main outlet of the shell, valves each oscillatory in a chamber inlet, valves each oscillatory in a chamber outlet, fingers for oscillating the valves individually, and cam rings secured to the faces of the web members and adapted to oscillate the valves in timed relation to the engine cycle.

5. In a rotary internal combustion motor,

a main frame, a pair of main bearings, journals secured therein, a shaft rotatable on the journals, a web member mounted on the shaft, an annular rim on the web member, 60 an annular shell mounted on the main frame in which the rim rotates, expandible packing rings in the periphery of the rim near the margins thereof contacting with the wall of the shells, side walls against the annular 65 faces of the shells, caps thereon covering the main bearings, the shell having a pair of combustion chambers formed therein each provided with an inlet and an outlet, an inlet boss on the shell the bore of which is in 70 communication through an eccentric space formed in the wall of the shell with the chamber inlets, an exhaust boss on the shell in communication with an outlet of each combustion chamber through an eccentric 75 space formed in the space of the shell wall, abutments longitudinally reciprocable in substantially radial slots in the web member, spring members pivotally mounted on the web member each engaging a pair of abutments for forcing the latter outwardly into the compression and expansion spaces, valves each oscillatory in a chamber inlet, a cam finger on each valve, a cam ring mounted on the shell adapted to operate the cam finger, 80 and an outlet valve mounted in each chamber outlet and provided with an operating cam finger, the ring being adapted to oscillate the latter finger.

6. In a rotary internal combustion motor, 85 a main frame, a drive shaft journaled therein, a circular casing with which the shaft is concentric, provided with compression and expansion spaces, a web member on the shaft filling and rotating in the chamber, abutments reciprocable radially in the web yieldingly projected to sweep through the chamber and the said spaces, the casing having a pair of combustion chambers in connection through the inlets thereof with the compression space and through the outlets thereof with the expansion space, rotatable valves 95 controlling the inlets and outlets and means adapted to operate the valves in timed relation to the engine cycle.

In testimony whereof I affix my signature in presence of two witnesses.

WILLIAM H. FLINN.
